UNITED STATES PATENT OFFICE.

EDWARD A. ECKERT, OF CINCINNATI, OHIO.

SWITCH-OPERATING ATTACHMENT FOR STREET-CARS.

SPECIFICATION forming part of Letters Patent No. 241,637, dated May 17, 1881.

Application filed April 1, 1881. (No model.)

To all whom it may concern:

Be it known that I, EDWARD A. ECKERT, of Cincinnati, Hamilton county, Ohio, have invented a new and useful Switch-Operating Attachment for Street-Cars, of which the following is a specification.

- My invention relates to a device to enable the driver of a street-car to operate a switch without leaving his post upon the car-platform.
- For this purpose I employ a vibrating member, which I call the "spider." This member has on opposite sides of it two projections, of which one extends obliquely forward and the other obliquely rearward. By means of a lever, or equivalent means conveniently located for the driver's use, he is enabled to bring one or other projection into service, according to whether he desires the switch to lead onto the main track or onto the siding.
- In the accompanying drawings, Figure 1 is a side elevation of a street-car platform provided with my switch-operating attachment, the parts being shown in the position assumed by them at the end of their stroke or movement for shifting the switch to the position for leading onto the siding. Figs. 2 and 3 are respectively a rear and front elevation of the attachment in the same position. Figs. 4 and 5 are similar elevations of the same in the reverse position.
- Figs. 6 and 7 are ground plans of the same in the first and second positions respectively. Fig. 8 is a top view of my spider detached. Figs. 9 and 10 are respectively a front and side elevation of a modification of my bar-guide.
- A A may represent customary main and side trams of a street-railway, a a' being the usual tread and guard flanges. B may represent a customary switch-point. C may represent a customary street-car platform.
- My switch-operating attachment is constructed as follows: A bracket or hanger, D, firmly attached to the platform, affords journal-bear-

ing for a shaft, E, to whose rear extremity is bolted my spider F, which has two claws, f f', of which that claw, f, which is on the side next to the siding projects obliquely rearward, and that claw, f', which is on the side next to the main track projects obliquely forward. A pin, f'', projecting from the spider engages with a spring, G, which tends to restore the spider, whenever left at liberty, to its normal and inactive position.

The forward extremity of the shaft E carries a crank, H, to which is connected a bar, I, whose wrist or handle i is conveniently located for manipulation by the driver. A keeper, J, serves to guide and hold the bar I in its normal or vertical position.

The operation is obvious: The driver, grasping the bar I, thrusts the crank H to the right or to the left, and in so doing vibrates the spider, and by its instrumentality shifts the switch in or out, as desired.

A modification of my bar-guide is shown at Figs. 9 and 10, in which the bar I is made to traverse a slotted head, K, whose stud k is journaled within the dash-board or car-body, so as to permit the said head to vibrate in conformity with the changing angles of the bar.

I claim as new and of my invention—

1. The switch - operating attachment for street-cars, consisting of the spider F f f' f'', spring G, shaft E, crank H, and bar I, substantially as set forth.

2. In combination with the spider F f f' f'', spring G, shaft E, crank H, and bar I, the vibrating head or guide K k.

In testimony of which invention I hereunto set my hand.

EDWARD A. ECKERT.
